UNITED STATES PATENT OFFICE.

BENJAMIN H. LEISTER, OF SAN FRANCISCO, CALIFORNIA.

HEATER.

Application filed July 13, 1920. Serial No. 395,978.

To all whom it may concern:

Be it known that I, BENJAMIN H. LEISTER, a citizen of the United States, residing at San Francisco, in the county of San Francisco and State of California, have invented 5 certain new and useful Improvements in Heaters, of which the following is a specification.

The present invention relates to improvements in heaters and particularly that type of heater employed for the generation of steam, and commonly known as the flash type.

One of the principal objects of the present invention consists in the employment of 15 a tube or pipe preferably of the seamless type flattened or compressed for a portion of its length to afford a fluid passage substantially oval in cross section and coiled 20 to position the relatively flat surfaces in substantially parallel relation affording alternating fluid and heat passages throughout the length of the coil.

A further object is to provide a coiled 25 tubular construction, between adjacent coils of which are positioned spacer members providing heat passages transversely of and between the coiled surfaces for approximately the full width of the tubes.

Another object of the invention is to 30 provide a coil structure of the flattened tubular type with means at the end of the coil substantially circular in cross section affording a strengthening and holding 35 means for the coil structure.

A further object is to provide a heater 40 of the coil type wherein a core is provided about which the fluid channel forming tube is coiled in convolute form, and wherein 45 spacer members secured to one surface of the tube are adapted to unite to adjacent surfaces of the tube forming convolute affording the spacers and heat channels between adjacent convolute forming coils.

A still further object is to provide a 50 means whereby adjacent convolute structures communicate with each other through their supporting cores and wherein adjacent convolute structures are separable from their co- 55 operating structures, and whereby a fluid passage is provided in opposite directions in adjacent coacting convolute structures.

With the above mentioned and other objects in view, the invention consists in the 55 novel construction and combination of parts hereinafter described, illustrated in the ac-

companying drawings, and set forth in the claims hereto appended, it being understood that various changes in the form, proportion, size and minor details of construction 60 within the scope of the claims may be resorted to without departing from the spirit or sacrificing any of the advantages of the invention.

To more fully comprehend the invention 65 reference is directed to the accompanying drawings, wherein—

Figure 1 is a view in side elevation partly in longitudinal section of a heater or furnace containing the preferred embodiment of my invention.

Figure 2 is a diagrammatic broken plan view of one of the convolute forming heaters.

Figure 3 is a sectional view taken on line 75 3—3 of Figure 2, viewed in the direction of the arrow.

Figure 4 is a central sectional view of the mounting core for adjacent convolutes.

Figure 5 is a detail sectional view of 80 the helix forming coil illustrated in Figure 1 of the drawings.

In the drawings wherein like characters of reference designate corresponding parts, 1 indicates a furnace constructed of any 85 suitable size and configuration provided with a chamber 2 surrounded by an insulating wall 3, and at one end formed with an opening 4 through which is adapted to project a heating element 5 of any suitable 90 type. The products of combustion are adapted to pass from the chamber 2 through the stack 6 and a forced draft passage 7 surrounds the insulating wall 3 and connects with the opening 4 through the stack 95 6 whereby, if desirable, a forced draft may be had between the stacks 6 and the chamber 2. The closure plate or door 8 is adapted for positioning over the opening 4, and is provided with a port through which the 100 heating element 5 extends. While the construction is illustrated in Figure 1 of the drawings as being disposed in horizontal position, it will be readily apparent that the same may be vertically disposed. 105

Within the chamber 2 is provided a suitable heater, one portion of which is in the form of a tube 9 rolled to provide relatively flat side walls 10 affording a substantially oval fluid passage 11 on its interior. The 110 tube is coiled uniformly throughout its length to provide a helix 12 disposed with

the flat walls 10 of adjacent coils forming the helix lying relatively close to each other as in Figure 1 of the drawings, and connected throughout the length of the helix by the 5 spacers 13 which extend the full width of the faces 10 affording heat passages disposed radially of the helix and further providing uniting means between adjacent coils of the helix to retain said coils in fixed position 10 relatively to each other at spaced intervals throughout the entire circumference of said helix. The coils of the tube at the terminal ends of the helix are substantially circular in cross section as at 14 providing 15 stiffening or strengthening means and affording an easy coupling connection between the ends of the helix and tubular members connected therewith. At the end of the helix structure 12 removed from the 20 member 5, I prefer to position a series of convolute tubular structures partly illustrated in Figures 2, 3 and 4 of the drawings, and the same are constructed in the following manner: The convolute structures, illustrated 25 in Figure 1 as four in number, are preferably arranged in batteries or pairs of two, and are formed by flattening a round or circular tube 15 to substantially oval formation for the majority of its length as at 16', in Figure 3 of the drawings. To one surface 30 of the relatively flat tube are secured at spaced intervals, spacer members 16, Figure 2 of the drawings, which when the tube is coiled to provide the convolute structure 35 contact with adjacent surfaces of succeeding coils, and are united therewith in any suitable manner as by welding. A core 17 is provided for each pair or battery of convolute structures and the same consists of the 40 parts 18 and 19 formed with a convolute peripheral surface provided with transverse slots 20 forming spaced transversely disposed spacer members 21 disposed radially of the surface of the members 18 and 19. 45 The members 18 and 19 are each provided on their interior with the fluid passage 22, said passage opening as at 23 adjacent the periphery of the members and communicate with each other preferably on the center of 50 the members as at 24. One of the members, preferably the member 18, is provided with a threaded stud 25 adapted for inserting in and projecting through the stud receiving opening 26 in the member 19, and said stud 55 25 is adapted for receiving a nut 27 for threading thereon to detachably secure said members 18 and 19 together. To afford a fluid tight joint between and adjacent contacting surfaces of the members 18 and 19, I 60 provide an annular flange 28 on one of the members, which is receivable in an annular recess 29 formed on one face of the other member, said flange 28 and recess 29 being provided with coacting bevelled surfaces 30 which are adapted to be wedged together 65

on the adjustment of the nut 27 on the stud 25. To hold the respective members 18 and 19 during the coiling of the convolute tubular structure about the same, I provide a countersink 31 in each of said members, said 70 countersink being illustrated as polygonal in plan.

In forming the convolute structures, one end of the tube 15 secured to the outlet 23 of the channel 22 of one of the sections of the 75 tube is coiled, as in Figure 2 of the drawings, about said core with successive coils forming the convolute structure contacting with the free ends of the spacer 16 carried on the tube surface, until the convolute structure 80 of the desired size is provided, after which time the free ends of the spacer 16 are welded or otherwise secured to the adjacent portions of succeeding coil surfaces whereby the coils forming the convolute are held in fixed 85 relation relative to each other, and heat passages are provided transversely of the coil surface for approximately their full width, as illustrated in Figures 1 and 3 of the drawings. The terminal wrapping or coil of the 90 convolute is substantially circular in cross section, as illustrated in Figures 2 and 3 of the drawings, affording a strengthening and holding means for the relatively flat convolute forming coils, and is offset at its terminal end from the plane of the remainder of the coil as at 32, which offset end is preferably threaded providing a means for coupling the end of the convolute to an adjacent convolute. 95

It will be apparent that by providing a two part separable core, each part mounting a convolute tubular structure, as above described, adjacent convolutes may be separately formed and subsequently positioned 105 with their adjacent edges in relatively close relation, and when desired may be detached to enable the repairing of the convolutes if the same is necessary. 110

I claim:

1. A heater comprising a tube providing a fluid chamber arranged in convolute form, and a single series of spacers separating adjacent convolutes of the tube and uniting the same one to the other to provide heat 115 passages between said adjacent convolutes of the tube, said spacers secured at one end to one face of the tube and contacting at their free ends with the adjacent face of an adjacent convolution permitting the expansion 120 and contraction of the convolute.

2. A heater comprising a tube providing a fluid chamber coiled to provide a convolute structure, a convolute channeled core about which said tube is coiled with one end of said tube connected with one end of said core channel, a plurality of spacers separating adjacent convolutions of said coil and separating the same one to the other to provide heat passages between 130

adjacent coils of the convolute, the outer coil of the convolute being secured to its inner adjacent convolute to prevent unwinding of said structure.

- 5 3. A heater comprising a pair of tubes coiled to provide a pair of convolute structures disposed one adjacent the other, a core about which each of said convolutes is coiled, said core consisting of a plurality of parts 10 each provided with a fluid channel one communicating with the other and each channel opening at the periphery of the core and connecting with the inner end of one of said convolutes, and means for detachably securing 15 said channeled core members together.

4. A heater comprising a pair of tubes coiled to provide a pair of convolute structures, the walls of adjacent convolutions lying in spaced relation to said convolute structures being disposed side by side in parallel spaced relation, spacers separating adjacent coils of the respective convolutions and uniting the same one to the other to provide 25 heat passages between adjacent coiled surfaces of the respective structures, a core about which said structures are wound, the same consisting of a two part member provided with a channel affording a communication from one convolute structure to the other, and means for detachably securing said core structure parts together.

5. A heater comprising a tube providing a chamber oval in cross section and coiled 35 in convolute form with adjacent surfaces in spaced relation, spacers separating the overlying surface of the convolutions and for uniting the same to fix one convolution relative to the other and to provide heat 40 passages adjacent separated convolutions, the outer convolution being substantially circular in cross section and offset at its terminal end from the main body of the convolutions.

- 45 6. A heater comprising a core having a volute peripheral surface provided with a plurality of spaced radial projections and formed on its interior with a fluid channel, a tube providing a fluid channel disposed 50 with one end connecting with one end of said channel, spacer members secured to one face of said tube, said tube coiled about said core to form a convolute structure with the free edges of said spacers contacting 55 with the surface of the adjacent coil providing means for separating the coils of the convolute, and forming heat passages extending transversely of said coils.

7. A heater comprising a core provided 60 on its edge with a plurality of radial spacer projections forming a volute periphery near said core, said core further provided with a channel opening at one end on the edge

of said core, a tube of oval cross section providing a fluid channel and disposed with one 65 end communicating with the end of said channel at its edge opening, spacer members secured to one exterior face of said tube, said tube being coiled about said core with the free edges of said spacers contacting 70 with the surfaces of the adjacent coil providing a convolute structure with separated convolute forming coils, said spacers providing means for fixing the coils one relatively to the other and providing heat passages extending transversely of said spaced coils for approximately their full width.

8. A heater comprising a core having a transversely serrated volute peripheral surface and formed on its interior with a channel opening at its center and at its peripheral surface, a tube connected at one end with the peripheral opening of said channel and coiled about said core providing a volute structure, spacer members extending 80 transversely of the tube between said volute forming coils providing heat passages disposed transversely of the coils and extending approximately the full width thereof, and said core being provided with a countersink 85 affording means for holding the same during the coiling of the tube about the same.

9. A heater comprising a pair of convolute tubular coils disposed side by side in spaced relation, a two part core on to 95 which the inner ends of said convolute forming tubes are secured, said core consisting of separable sections each provided with a fluid channel communicating with each other, and each opening through the 100 periphery of their respective section providing connection between the respective convolutes and the core, one of said sections provided with a stud, the other section being provided with an opening for 105 receiving said stud, a nut for securing to said stud to detachably secure said sections together, said sections being further provided with a countersink affording means for holding the same during the coiling of 110 the tubes about the same.

10. A heater comprising a tube providing a fluid chamber arranged in convolute form, standards secured to one face of the tube and contacting at their free ends with an 115 opposite face of the tube providing heat passages between said adjacent convolutes of the tube and permitting the expansion and contraction of the convolute on the same being subjected to different temperatures, the outer coil of said convolute being 120 cylindrical in cross section.

In testimony whereof I have signed my name to this specification.

BENJAMIN H. LEISTER.
